UNITED STATES PATENT OFFICE.

LESLIE CHATHAM ORRELL, OF BELLEVUE, KENTUCKY.

FUSE-HOLDER.

SPECIFICATION forming part of Letters Patent No. 542,713, dated July 16, 1895.

Application filed October 22, 1894. Serial No. 526,574. (No model.)

To all whom it may concern:

Be it known that I, LESLIE CHATHAM ORRELL, a citizen of the United States, and a resident of the city of Bellevue, in the county of Campbell and State of Kentucky, have invented certain new and useful Improvements in Fuse-Holders, of which the following is a specification.

The several features of my invention and the various advantages resulting from their use, conjointly or otherwise, will be apparent from the following description and claims:

In the accompanying drawings, making a part of this application, and to which reference is hereby made, Figure 1 represents a plan view of a fuse-holder embodying my invention, but without those features of invention which relate to the cover, the cover being absent from this sketch. Fig. 2 is a vertical section thereof in the plane of the dotted line 2 2 of Fig. 1. Fig. 3 is an end elevation of the holder, shown in Fig. 1. Fig. 4 is a vertical transverse section taken in the plane of the dotted line 4 4 of Fig. 6 and showing the cover in position on the holder. Fig. 5 is an end view of the fuse-holder and cover. Fig. 6 is a top or plan view of the cover. Fig. 7 is a detail plan view of the fuse-wire, showing how it is bent and where cut off when applied to the fuse-holder. Fig. 8 is an elevation of one portion of the fuse-holder, showing the mode of operating it when putting the fuse in place. Fig. 9 is a top view of the stationary piece or plate and of the sliding piece separated from one another. Fig. 10 is a side or edge view of the sliding piece.

A indicates the base or supporting-block. In this block are the recesses B B, preferably of equal size. (See Fig. 2.) In each end portion of the block is located a device for holding the adjacent end of the fuse. Each of these devices is alike and constructed as follows: The upper plate or part C² of an angulated metallic stationary piece C rests upon the upper surface of the block A. The middle plate or portion C³ of this piece C is vertical and lies against the adjacent wall of the recess B. The lower end or plate C⁴ of the piece C extends across the recess upon the bottom of the latter. Each side edge of the vertical portion C³ of the piece C is provided with a wing or extension C⁵ bent around in

front of the part C³ and toward the vertical center of the latter, thus forming a loop D.

The sliding piece E consists of a horizontal portion E² and a vertical portion E³. When the piece E is in position, the vertical portion E³ is in the loop D, as shown. There is a guiding opening E⁴ in piece E, and through this passes rod F, fixed at base, preferably as shown, by being screwed or riveted to the lower plate C⁴ of the piece C. This rod F serves to guide the one end of the sliding piece E, while the conjunction of part E³ of the latter with the loop D, as mentioned, serves to guide the other end of said piece E. At the top end of the rod F and above the sliding piece E is fixed a head or contact-piece H for engagement with the fuse-wire.

A suitable spring K, preferably a coiled one, embracing the rod F, as shown, and compressed between a suitable base, as plate C¹, and the part E³ of plate E serves to continually press the latter toward head H.

The stationary piece C is suitably held in position, preferably, by a bolt or screw J extending up through the block A and engaging a thread in the part C² of piece C.

The contact L for the line-wire consists of a screw L², having a head L³, preferably accompanied by a washer L⁴ on the shank of the screw, the latter entering the plate C² and screwed therein.

Suitable means for fastening the block are to be employed—a preferred means being the screw M, passing through the center of the block A and screwing into the support, to which the fuse-holder block A is connected.

The block A is preferably made of porcelain.

I have constructed an appropriate cover for the fuse-holder. This cover is preferably made of enameled ware. The cover N consists of a top piece N² and flanges N³, extending down from the end edges of the top, and flanges N⁴ extending down from the side edges of the top. To two opposite flanges, as N⁴ N⁴, are respectively secured spring-catches P, which engage detents R of the holder at their respective sides thereof. I have devised a preferred form of these catches, to wit: that shown, consisting of a spring-plate having a bent or bowed portion P², received into a similar-shaped (concave) recess R² in the adjacent side of the block A. In consequence of the

inclinations of the bowed portion of the catch, the latter will be unlatched by a forceful pull on the cover, withdrawing it from the block A, and can be latched thereto by pressing the cover on and toward the block. Suitable room for the latches to move back is provided. A preferred provision for this purpose consists of the recesses N⁵ in the cover.

I will now proceed to describe the mode in which the fuse-holder is operated and operates. One end of a fuse-wire, as S, of the desired thickness is bent to form a hook, substantially as shown in solid lines in Fig. 7. One of the sliding pieces E—take, for example, the right-hand one (see Figs. 2 and 8)—is depressed. An easy way of so doing is by means of a small screwdriver, knife-blade, lead-pencil, or the like. The hooked end of the fuse-wire S is bent around the rod F above piece E and below the contact H. Downward pressure on the piece E is then released, and the latter, impelled by the spring K, rises and presses the wire S against the contact H. This end of the wire S is thus firmly secured in place. The wire S is now drawn taut in the direction of the other or left-hand contact H. The sliding piece E under this contact is now depressed and the taut wire brought against the rod F of said piece E, above the latter and beneath the contact H, is then bent around the rod F, substantially as shown in dotted lines in Fig. 7. The sliding piece E is now allowed to rise and the wire is gripped securely between it and the contact H above. The fuse is readily cut off from the rest of the wire by the end of a screwdriver or a knife. The fuse is now in place and will remain in position until burned out by an electric current of greater power than the fuse will carry. The operation of a fuse and its purpose in relation to the transmission and prevention and diversion of electric currents is too well known to justify any explanation here. Among the various advantages of my invention may be mentioned the following, to wit: The fuse can be readily placed in position in an accurate manner. The desired length of fuse can always be obtained. There is no danger of putting on too much fuse or of bending it around the contact in an improper manner.

In the ordinary method of attaching the fuse—viz., putting it under a nut and screwing down the latter—the fuse-wire is liable to become wound on itself, so as to cause too much fuse to be present. In such event the fuse is often stretched too much and the carrying capacity of it is diminished, and it often melts long before the amount of electric current which would be injurious is reached. For example, suppose its carrying capacity is three ampères; by stretching the fuse its capacity may be reduced one-half an ampère. It will be burned out by a current not sufficient to do the ordinary work required, it being understood that the amount of electric

current required is between two and three ampères. In other cases the nut in being screwed up breaks the fuse and wastes it. In still other cases the nut in being screwed up loops the fuse more or less, and to that extent increases its carrying capacity beyond what it was intended to carry, and thereby causes it to convey a current injurious to the instrument or machine, &c., which a current of a given strength is designed to operate.

It will be understood that my device can be used for any desired strength of current. This I accomplish by increasing the thickness of the fuse-wire, and I am enabled to readily apply this wire, (of any desired thickness,) because the construction of my gripping device enables me so to do.

Where the cover is made of enameled ware, it will for economy of manufacture be bulged at W W to provide recesses N⁵ N⁵, wherein the springs may react when the latter are pushed back in the act of locking the cover on the holder-block or unlocking it therefrom.

It is proposed to frequently associate one or more sets of fuse-holders together upon the same block, substantially as shown.

What I claim as new and of my invention, and desire to secure by Letters Patent, is—

1. In a fuseholder, the piece C³, having the loop D, and the piece E having part E³ sliding in loop D, and a contact as H over the piece E², and means for elastically pressing the piece E against the contact, substantially as and for the purposes specified.

2. In a fuse holder, the piece C³, having the loop D, and the piece E having part E³ sliding in loop D, and a contact as H over the piece E², and means for elastically pressing the piece E against the contact, and rod F passing through the piece E² and carrying the said contact, substantially as and for the purposes specified.

3. The combination of the piece C³, loop D thereof, piece E having pieces E² and E³, the latter engaging the loop D, rod F extending through piece E², contact H on the said rod, and spring K embracing said rod behind piece E², substantially as and for the purposes specified.

4. The combination of the angulated pieces C² and C³, secured together, and the wings C⁵ in one with piece C³, and piece E having parts E² E³, of which E² engages the wings C⁵, rod F through part E², and superincumbent contact H, spring K pressing piece E toward contact H, substantially as and for the purposes specified.

5. The combination of the angulated piece C having part C³, and bottom extension C⁴, and loop D, and sliding piece E, having parts E², E³, the latter engaging the loop and rod F fixed in bottom C⁴, and passing through the part E², and contact H, on the upper end of said rod, and spring for elevating said piece E, substantially as and for the purposes specified.

6. The combination of the angulated piece C having the piece C², part C³, and bottom extension C⁴, and loop D, and sliding piece E, having parts E², E³, the latter engaging the loop and rod F fixed in bottom C⁴, and passing through the part E², and contact H, on the upper end of said rod, and spring for elevating said piece E, and the line contact adjustment L fixed to piece C², substantially as and for the purposes specified.

7. The combination of the angulated piece C having the piece C², part C³, and bottom extension C⁴, and loop D, and sliding piece E, having parts E², E³, the latter engaging the loop and rod F fixed in bottom C⁴, and passing through the part E², and contact H, on the upper end of said rod, and spring embracing the rod F, for elevating said piece E, and the line contact adjustment L fixed to

piece C², substantially as and for the purposes specified.

8. In a fuse holder, the block A having recesses B, the combination with the block of the following to wit: a piece C having top plate C² on top of block, vertical part C³ at 25 wall of recess, and having loop D, bottom extension C⁴, at bottom of recess, and piece E whose part E³ enters said loop D, rod F fixed to extension C⁴, and extended through part E², and contact H thereon, a coiled spring K 30 embracing the rod F between extension C⁴ and part E², and located in said recess, substantially as and for the purposes specified.

LESLIE CHATHAM ORRELL.
